FOLDING CHAIR

Enfred W. Anderson and Arvid J. Anderson,
Norway, Mich.

Application August 18, 1950, Serial No. 180,118

7 Claims. (Cl. 155—140)

1

This invention appertains to folding or collapsible furniture and more particularly to a novel chair which can be readily collapsed or opened by the mere raising or lowering of the chair seat.

One of the primary objects of our invention is to provide a folding chair, which, when set up for use will be extremely strong and sturdy, and which will give the appearance of a permanent full sized chair, and which when folded will occupy a minimum amount of space for storage and be capable of standing upright alone on its four legs.

Another salient object of the invention is the provision of a collapsible chair embodying companion like side frames, with means whereby the frames can be hinged for swinging movement toward or away from one another by the use of a single pivot bolt.

A further object of our invention is the provision of a chair seat, so formed that the same can be upholstered, if so desired, hingedly carried by one side frame with a novel linkage connecting said side frames, actuated by the raising and lowering of the seat for moving the frames to a spread open position or to a collapsible, substantially vertical position.

A further important object of the invention is to provide means for locking the linkage when the seat is in its lowered position for bracing the chair and its linkage.

Another further object of the invention is to provide additional latch links movable upon the opening and closing of the chair for preventing outward spreading of the side frames beyond a predetermined point when the chair is open for use.

A still further object of the invention is the provision of a novel backrest for the chair carried by the pivot bolt for the side frames, movable to an operative back supporting position and to a collapsed, substantially vertical position, with means whereby the backrest is automatically tightened relative to the side frames as the backrest is moved to its operative horizontal position, so that accidental movement of the backrest will be eliminated while the chair is in use.

A still further important object of the invention is to provide a folding chair of the above character which will be durable and efficient in use, one that will be simple and easy to manufacture and one which can be placed upon the market at a reasonable price and which will possess an attractive and substantial appearance.

With these and other objects in view, the in-

2

vention consists in the novel construction, arrangement and formation of parts, as will be hereinafter more specifically described and claimed and illustrated in the accompanying drawings, in which drawings,

Figure 1 is a side elevational view of our chair in its set up open position ready for use.

Figure 2 is a front elevational view of the chair showing the same in its open set up position.

Figure 3 is a central vertical sectional view taken on the line 3—3 of Figure 2, looking in the direction of the arrows.

Figure 4 is a fragmentary horizontal sectional view taken on the line 4—4 of Figure 3, looking in the direction of the arrows and illustrating the linkage connection between the side frames.

Figure 5 is a fragmentary transverse sectional view through the chair taken on the line 5—5 of Figure 3, looking in the direction of the arrows, the view also illustrating the linkage.

Figure 6 is a view similar to Figure 5 but showing the chair in its folded, collapsed position.

Figure 7 is an enlarged fragmentary detailed transverse sectional view through the chair taken on the line 7—7 of Figure 3, looking in the direction of the arrows, said view also illustrating the novel linkage.

Figure 8 is a fragmentary rear elevational view showing the backrest in its operative position in full lines and in its folded position in dotted lines.

Figure 9 is a detailed sectional view through the back of the chair taken on the line 9—9 of Figure 3, looking in the direction of the arrows, showing the chair in its set up position.

Figure 10 is a view similar to Figure 9 but showing the chair in its folded position.

Figure 11 is a detailed horizontal sectional view through the back of the chair taken on the line 11—11 of Figure 9, looking in the direction of the arrows.

Referring to the drawings in detail, wherein similar reference characters designate corresponding parts throughout the several views, the letter C generally indicates our novel folding chair.

This chair C includes a pair of companion like side frames 15 and 16, a chair seat 17 and a backrest 18.

The frames 15 and 16 can be fabricated in any preferred manner, and for the purpose of illustration, the side frame 15 includes a top rail 19, front and rear legs 20 and 21. A back upright 55 22 is secured to the extreme rear end of the side

rail 19. The side frame 16 also includes a top rail 23, front and rear legs 24 and 25 and a back upright 26. The front legs and back legs preferably diverge toward the lower ends, in order to provide a spread base for the chair, and obviously the front leg 20 and the rear leg 21 of one side frame and the front leg 24 and the rear leg 25 of the other side frame can be connected adjacent to their lower ends by brace rungs if so desired. The upper ends of the back uprights 22 and 26 have rigidly secured thereto inwardly extending overlapping plates 27 and 28. The plate 27 is of a material of greater thickness than the plate 28 and these plates are pivotally connected by a centrally disposed pivot bolt 29. The bolt is held against turning movement relative to the plate 28 by counter sinking the polygonal portion of the bolt in said plate. The threaded end of the bolt projects forwardly in front of the plates 27 and 28 for a purpose which will be later set forth. The upright 22 has its rear face notched as at 30, so that when the side frames 15 and 16 are swung on the bolt to their open position, the lower corner of the plate 28 will abut against said shoulder and act as a stop.

The edge of the plate 27 adjacent to the back upright 26 is angled as at 31 and 32, and the edge 31 also acts as a stop for engaging the upright 26 when the side frames 15 and 16 are swung to an open position. The edge 32 acts as a stop for these side frames when the side frames are swung toward one another to their collapsed position, and the back upright 26 will abut to said edge 32 (see Figure 10).

Now referring to the backrest 18, it can be seen that the same includes a back board 33, and this back board can be provided with any preferred type of upholstering 34. Secured to the central portion of the back board on the inner face thereof is a cap nut or internally threaded socket 35, and this nut or socket 35 is adapted to receive the threaded end of the pivot bolt 29. A friction washer 36 is preferably placed on the bolt and secured to the plate 27, and a similar friction washer 37 is carried by the back board 33 and receives the bolt when the bolt is threaded into the socket or nut 35. By this arrangement, the backrest can be moved to a horizontal operative position, as shown in Figures 1, 2, 3, 5, and 8, or to a collapsed vertical position, as shown in Figure 6.

In actual practice the back 18 is threaded on the bolt, and when the backrest is turned to its horizontal operative position, the backrest tightens up on the bolt with the friction washers in binding contact, and in effect, the plates 27 and 28 are also brought into intimate tight contact. This prevents accidental swinging movement of the backrest out of its operative position. When the backrest is swung to its vertical position, the same loosens or unthreads on the bolt, and the plates 27 and 28 are loosened. To limit the swinging movement of the backrest, the same has rigidly secured thereto a stop block 38, and this block is so positioned as to engage the lower edge of the plate 27 when the backrest is in a horizontal position and to abut the back upright 26 when the same is moved to its vertical position.

The chair seat 17 includes a marginal frame 39 to which is secured a seat board 40. The seat can be provided with upholstery 41 should such be desirable. Hinges 42 pivotally connect one side of the seat to the rail 19 of the side frame 15, so that the seat can be swung to either a

horizontal position over the frame 16 (see Figures 5 and 7) or to a substantially vertical position (see Figure 6). When the seat 17 is swung to its lowered position, and when the frames 15 and 16 are in their open spread position, the seat frame 39 rests upon the upper faces of the rails 19 and 23 of the side frames 15 and 16. In order to provide a rigid structure, the rail 23 and the adjacent edge of the seat frame 39 can be provided with companion pins and sockets 43 and 44. Obviously, the pins 43 will be received in the sockets when the seat is lowered as is best shown in Figure 7. The front edge of the seat projects beyond the front legs 15 and 16, and the seat has rigidly secured thereto a depending horizontal skirt board 45 which extends in front of the legs and front edges of the legs 19 and 23 and give the chair a finished and desired appearance. If preferred or desired a flexible skirt 46 can be carried by the rear end of the seat 17 for hiding certain mechanism which will now be described.

Forming an important feature of the invention is the provision of means for automatically moving the side frames 15 and 16 toward and away from one another upon the raising and lowering of the seat 17. This means includes companion front and rear toggles 47 and 48. Each of the toggles includes companion levers 49 and 50. The inner ends of the levers 49 and 50 of each toggle are pivotally connected by pivot pins 51, and these pivot pins in turn carry a longitudinally extending operating rod 52. Hence, the toggle levers 47 and 48 are operatively connected together as a unit. The outer ends of the levers 49 and 50 of the toggles 47 and 48 are pivotally connected as at 53 to suitable brackets 54 carried by the inner faces of the rails 19 and 20 of the side frames 15 and 16. Rockably mounted upon the pivot pins 51 are front and rear like operating links 55, and these links have their upper or outer ends pivotally connected as at 56 to the bottom of the seat 17 at one side of the hinges 42.

In operation, and considering that the chair is in its set up position with the seat 17 over the side frames 15 and 16, and it is desired to fold or collapse the chair, the chair back 18 can be swung to its horizontal position as heretofore described after which the side edge of the seat 17 remote from the hinges 42 is grasped and swung upwardly toward a vertical position. This will draw up on the links 55 and the links 55 in turn will pull up on toggles 47 and 48, and the levers 49 and 50 thereof will bring the side frames toward one another and into a vertical position as shown in Figure 6. When it is desired to open the chair, the edge of the chair seat remote from the hinges is again grasped, and the seat is swung down. The links 55 will push down on the toggles 47 and 48 and push the side frames away from one another. This movement can be aided by grasping the side frame 16 and pulling the same away from the side frame 15 as the chair seat 17 is lowered. At this point, it is to be noted that a part of the brace for the chair bottom 17 is centrally notched as at 58 which constitutes a keeper for the rod 52, and consequently, the toggles are held down in their lower spread position. To prevent the side frames 15 and 16 from spreading out too far under the weight of a person, front and rear pair of links 57 and 58 are provided. The outer ends of the links are pivotally connected to the pivot pins 53 for the outer ends of the toggles and the inner ends of the pair of links 57 and 58 are pivotally connected together by pivot pins 59. One link of each pair

carries a stop pin 60 and the other pair of the links carry a stop shoulder 61 which interengage when the links reach their substantially horizontal position, as shown in Figure 7.

Attention is also called to the fact that when the chair is in its open position, the legs of the side frames also diverge outwardly from one another. Hence, a broad solid foundation is provided for the chair.

Particular attention is also directed to the fact that when the chair is in its collapsed folded position that the side frames are in a substantial vertical position, and that the legs will still act as a support for the chair, so that the chair will stand alone even in its collapsed position (see Figure 6).

It is to be understood that one example only of the chair has been shown and described, and that various changes in details of construction may be made providing the same do not depart from the spirit or the scope of the invention.

We claim:

1. A folding chair comprising a pair of like companion side frames, each of said frames including a top rail, depending front and rear legs, and a back upright, a pivot bolt pivotally connecting the side frames together adjacent to the upper ends of the uprights, whereby said frames can be moved toward and away from one another, a chair seat hingedly connected to the rail of one frame and movable to an operative position over the rail of the other frame when said frames are in their open spread position, and a back rest mounted on said bolt for swinging movement, and said back rest being threaded on said bolt and movable to a tightened position on the bolt against the side frames when said back rest is swung to an operative horizontal position.

2. A folding chair comprising a pair of like side frames, each of said frames including a top rail, depending front and rear legs and back uprights, means pivotally connecting the uprights together adjacent to the upper ends of the side frames, whereby said frames can be moved toward and away from one another to a collapsed or to an open position, a seat hingedly secured to the rail of one side frame movable to a vertical non-operative position and to a lowered operative horizontal position over the top rails of the frames, and means for automatically moving the side frames toward and away from one another upon the raising and lowering of the seat, said means including front and rear pairs of toggles, each pair of toggles including levers pivotally connected together at their inner ends and pivotally connected at their outer ends to the side frames and operating links pivotally connected to the toggles at the pivot points of the levers and to the said seat.

3. The folding chair as defined in claim 2, and a rod connecting said front and rear toggles together at their pivot, whereby said toggles will work in unison, and said seat having a keeper notch for receiving said rod when the seat is in a lowered position.

4. The folding chair as defined in claim 2, and latch links pivotally connected at their outer ends

to the frames and pivotally connected together at their inner ends, and means for limiting the swinging movement of the links relative to one another.

5. The folding chair as defined in claim 2, and pins carried by the rail of the side frame opposite to the rail carrying the seat, and said seat having sockets adapted to receive the pins when the seat is in its lowered position and the frames are in their spread open position.

6. A folding chair comprising a pair of like companion side frames, each of said frames including a top rail, depending front and rear legs, and a back upright, overlapping plates carried by the upper ends of the uprights, a pivot bolt connecting said plates together, whereby said frames can be moved toward and away from one another, a chair seat hingedly connected to the rail of one frame and movable to an operative position over the rail of the other frame when said frames are in their open spread position, said pivot bolt being between and spaced from the upper ends of the side frames, whereby to space the side frames one from the other to form a base when the side frames are in their collapsed position, and a back rest mounted on said bolt for swinging movement, said back rest being threaded on said bolt and movable to a tightened position on the bolt against said plates when said back rest is swung to an operative horizontal position.

7. A folding chair comprising a pair of like side frames, each including a top rail, dependent front and rear legs and a back upright, means pivotally connecting the side frames together adjacent to the upper ends of the uprights, whereby the side frames can be swung toward and away from one another, a seat hingedly secured to the rail of one side frame movable to a substantially vertical collapsed position and to a substantially horizontal position over the side frames, an operable connection between the seat and side frames for moving the side frames toward and away from one another by the raising and lowering of the seat, and said operable connection including toggles having toggle levers pivotally connected together at their inner ends and pivotally connected to their side frames at their outer ends, and links pivotally connecting the toggles at the pivot point of the toggle levers to the seat.
